US0D1113213S

(12) **United States Design Patent** (10) **Patent No.:** **US D1,113,213 S**
(45) **Date of Patent:** **** Feb. 17, 2026**

(54) **CHAIR**

(71) Applicant: **Exemplis LLC**, Cypress, CA (US)

(72) Inventors: **Adam Huennekens**, Fullerton, CA (US); **Mitchell Mulder**, White Salmon, WA (US); **Mark Maul**, Whittier, CA (US)

(73) Assignee: **Exemplis LLC**, Cypress, CA (US)

(**) Term: **15 Years**

(21) Appl. No.: **29/749,618**

(22) Filed: **Sep. 8, 2020**

Related U.S. Application Data

(62) Division of application No. 29/650,972, filed on Jun. 11, 2018, now Pat. No. Des. 898,496.

(57) **CLAIM**

The ornamental design for a chair as shown and described.

DESCRIPTION

FIG. 1 is a top, rear, and right side perspective view of a chair;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines in the figures depict portions of the chair that form no part of the claimed design.

1 Claim, 7 Drawing Sheets
